(57) **CLAIM**

The ornamental design for a pipette strip, as shown and described.

DESCRIPTION

FIG. 1 is a front elevation view of the first embodiment of a pipette strip showing a single pipette showing our new design; FIG. 2 is a back elevation view of the pipette strip of FIG. 1; FIG. 3 is a left side view of the pipette strip of FIG. 1; FIG. 4 is a right side view of the pipette strip of FIG. 1; FIG. 5 is a top plan view of the pipette strip of FIG. 1; FIG. 6 is a bottom plan view of the pipette strip of FIG. 1; FIG. 7 is a back perspective view of the pipette strip of FIG. 1;

FIG. 8 is a front elevation view of the second embodiment of a pipette strip showing 3 connected pipettes; FIG. 9 is a back elevation view of the pipette strips of FIG. 8; FIG. 10 is a left side view of the pipette strip of FIG. 8; FIG. 11 is a right side view of the pipette strip of FIG. 8; FIG. 12 is a top plan view of the pipette strip of FIG. 8; FIG. 13 is a bottom plan view of the pipette strip of FIG. 8; FIG. 14 is a back perspective view of the pipette strip of FIG. 8;

FIG. 15 is a front elevation view of a third embodiment of a pipette strip showing 6 connected pipettes; FIG. 16 is a back elevation view of the pipette strip of FIG. 15; FIG. 17 is a left side view of the pipette strip of FIG. 15; FIG. 18 is a right side view of the pipette strip of FIG. 15; FIG. 19 is a top plan view of the pipette strip of FIG. 15; FIG. 20 is a bottom plan view of the pipette strip of FIG. 15; and, FIG. 21 is a back perspective view of the pipette strip of FIG. 15.

All broken lines and accompanying scissors depict unclaimed environment and form no part of the claimed design.
